FIG. 1 is a perspective view of the pan.

FIG. 2 is a side view of the pan shown in FIG. 1.

FIG. 3 is another side view of the pan shown in FIG. 1.

FIG. 4 is front view of the pan of FIG. 1.

FIG. 5 is a rear view of the pan of FIG. 1.

FIG. 6 is a top view of the pan of FIG. 1; and,

FIG. 7 is bottom view of the pan of FIG. 1.

The present application is directed to the design illustrated in the drawings. The broken line portions of the disclosure are for illustrative purposes only and form no part of the claimed design.
